ALMER A. ROUSSEAU, OF DALLAS, TEXAS.

LENS-GRINDING MACHINE.

1,069,818.

Specification of Letters Patent. Patented Aug. 12, 1913.

Application filed September 20, 1912. Serial No. 723,052.

To all whom it may concern:

Be it known that I, ALMER A. ROUSSEAU, a citizen of the United States, residing at 1904 Commerce street, Dallas, in the county of Dallas and State of Texas, have invented certain new and useful Improvements in Lens-Grinding Machines, of which the following is a specification:

My invention relates to new and useful improvements in lens grinding machines, and its object is to provide a machine which through a simple substitution of parts may be employed for grinding and polishing any sort of cylinder lens, either toric, convex or 15 concave.

Another object of the invention is to provide a lens grinding machine, in which both the lens and the grinding tool will be subjected to a reciprocating motion, the two motions being at right angles with each other.

A further object is to provide a means by which the length of strokes of the reciprocating part may be adjusted to a fine degree 25 of accuracy.

A still further object is to provide a means for maintaining a constant pressure between the lens which is being ground and the grinding tool.

With these and various other objects in view, my invention has relation to certain novel features of the construction and operation, an example of which is described in the following specification, and illustrated in the accompanying drawings, wherein:

Figure 1 is a top view of the base upon which the operating mechanism of the machine is mounted, the cover portion of the 40 machine not being shown in this view. Fig. 2 is transverse sectional view of the complete machine, the section being taken closely adjacent to one extremity of the machine. Fig. 3 is longitudinal vertical sectional view of the machine, the section being taken closely adjacent to the front wall of the machine casing. Figs. 4 and 5 are respectively a top and front view of an eccentric crank bearing, several of which are 45 embodied in the mechanism of the machine. Figs. 6 and 7 are respectively a longitudinal sectional view and a top view of a mechanism for holding a lens during the process of grinding the same, the means for reciprocating the same being also shown. Figs. 8 and 9 are respectively a side and top

view of a tool supporting bar showing the mechanism for communicating a reciprocating motion to said bar. Fig. 10 is a detail vertical sectional view taken upon the line X—X of Fig. 3, this view showing the tool supporting bar with one of the grinding tools and a dust guard correlated with said part. Fig. 11 is a detail view showing the mechanism for exerting a constant pressure upon the lens holding arm, showing also a device for releasing said arm from its operative position.

Referring now more particularly to the drawings, wherein like reference characters designate similar parts in all the figures, the numeral 1 denotes a rectangular base upon which the mechanism of the machine is mounted. Said mechanism is driven by a crank shaft 2 spaced a short distance from the rear edge of the base 1. The shaft 2 is mounted in bearings 3 and has one of its extremities provided with a fast and a loose driving pulley 4. The shaft 2 is provided with two oppositely extending cranks 5, each of which is adapted to communicate a reciprocating motion to a bar 6 through a pitman 7. The journal portion of each crank 5 is eccentrically mounted within a disk 8, said disk being formed in two halves, as is clearly shown in Fig. 5. Each half of the disk 8 is provided with two key-ways 8^a and the journal portion of each crank 5 is provided with two diametrically opposite keys 8^b adapted to enter an opposite pair of the key-ways 8^a. Each two part disk 8 is rotatably mounted in a suitable bearing provided upon the correlated extremity of each pitman 7. By mounting the disks 8 in various positions of angular adjustment 85 relative to the journal portion of the correlated crank, it is made possible to secure a delicate adjustment in the length of the strokes of each reciprocating bar 6. Each of the reciprocating bars 6 is provided with a longitudinal slot 9 into which there projects a guide block 10 supported from beneath by a pair of standards 11. The two standards 11 supporting each block 10 rest upon the base 1. The base is provided with a cover 11^a which is sufficiently elevated above the mechanism so far described as to clear the same. The cover 11^a is supported in an elevated position by front, back and end walls, the lower edges of which rest 105 upon a seat 11^b extending about the rim of the base 1. Each block 10 is surmounted by

a plate 12 contiguous with the top surface of the correlated bar 6 and serving to prevent upward displacement of said bar during its reciprocating motion. The two bars 6 are parallel and extend forwardly at right angles to the crank shaft 2 as is clearly shown in Fig. 1 of the drawings. The forward extremity of each bar 6 is connected through a hinge joint 13 with an arm 14, 10 which arm, in its normal position, is aligned with the correlated bar 6. The forward portion of each arm 14 is arched as indicated at 15, and a downwardly projecting pin 16 is mounted at the center or highest point of 15 the arch 15. A centrally apertured disk 17 is adapted to be mounted upon the pin 16 within the recess formed by the arched portion of each arm 14. The lens in its rough or unground form is secured to the under 20 face of the disk 17 by cement or any other suitable means, as indicated by the numeral 17^a in Fig. 6.

A description will now be given of the means employed for holding the grinding 25 tool and for communicating a reciprocating motion to the same. A shaft 18 is mounted at right angles to the shaft 2 in a pair of bearings 19 secured to the base 1, said shaft being adapted to receive rotation from the 30 shaft 2 through a pair of intermeshed bevel gears 20. The forward extremity of the shaft 18 is provided with a crank arm 21 which is adapted to communicate a reciprocating motion to a bar 22 through a pitman 35 23. The bar 22 is parallel and adjacent to the front edge of the base 1 and extends across an aperture 24 extending into the base 1 from the front edge thereof. At each 40 side of the aperture 24 a slide bearing 25 is mounted upon the base 1 to receive the reciprocating bar 22. The bar 22 furnishes a support for two grinding tools of mushroom shape, the head 26 of each tool being somewhat elongated in one direction, this elongated dimension being made parallel to the bar 22 when the tools are operatively mounted. Each tool is provided with a downwardly projecting shank 27 fitting into a suitable socket provided in the bar 22. 50 The space intervening between the two grinding tools 26 is equal to the space existing between the two reciprocating bars 6, and the relation of the parts is such that when the bars 6 and bars 22 occupy positions intermediate of their reciprocating stroke, the center points of the lenses secured to the blocks 17^a will have contact with the center points of the grinding tools 26. The grinding tools are restricted from vertical 55 displacement relative to the bar 22 by horizontal pins 28 passing through the bar 22 and partially recessed in the shank members 27. A metal dust guard 29 is correlated with the grinding tools 26, said guard being 60 clamped between the bar 22 and the tool 26,

as is clearly shown in Fig. 10 of the drawing.

A description will now be given of the mechanism employed to hold the lenses in constant contact with the grinding tools 70 during the operation of the machine. Upon the top 11^a of the cover adjacent to the front edge thereof, are mounted two brackets 30, the distance between said brackets being equal to that existing between the bars 6. 75 Upon each bracket 30 is pivoted the lower extremity of an arm 31, which arm during the operation of the machine occupies an upright position, as shown in the drawings, in full lines. Upon the lower extremity of the arm 31 is pivotally mounted the apex of a forwardly projecting bell-crank comprising an upper arm 32 and a lower arm 33. The free extremity of the arm 33 carries upon its under surface two spaced recesses 34, either 80 one of which may be brought into engagement with a horizontal pin 35 carried by a bracket member 36 mounted upon the foot of the bracket 30. When the uppermost of the two recesses 34 engages the pin 35, as 85 is shown in full lines in the drawings, the arm 31 will occupy an upright position. When the lowermost recess 34 engages the pin 35, the arm 31 will be inclined rearwardly at an angle with the vertical, as is 90 shown in dotted lines in Fig. 11 of the drawings.

Upon the upper extremity of the arm 31 is mounted a forwardly projecting arm 37 which is adapted to be adjusted in various 100 positions with relation to the arm 31 by means of a set-screw 38. Between the free ends of the bell-crank arm 32 and the middle portion of the arm 37, a rod 39 is extended, the extremity of said rod being pivotally 105 connected to the arm 32, and the upper extremity of said rod being free to slide in the aperture in the bar 37 through which said rod passes. Upon the rod 39 is mounted a coiled spring 40 having its extremities 110 respectively abutting against the arm 37 and the bell-crank arms 32. The downward pressure exerted by the spring 40 upon the free end of the arm 32 serves to impress an impulse toward downward motion upon the bell-crank arm 33 and thereby prevent the recessed portion 34 of said arm from escaping from engagement with the pin 35. The 115 upper bell-crank arm is provided with an upwardly projecting handle member 41, which, when subjected to rearwardly acting pressure, produces a rotation of the bell-crank about its pivotal support and serves to free either recess 34 from engagement with the pin 35. Between the forward extremities of the arm 37 and the arm 14, a rod 42 is extended, said rod having its lower end pivotally connected with the arm 14 and its upper extremity adapted to undergo a 120 sliding displacement through the free end of 125 the arm 37.

the arm 37. Upon the rod 42 is mounted a coiled spring 43 having its upper and lower extremities respectively bearing against the arms 37 and 14. Since in the operative position of the mechanism, the arm 37 is rigidly maintained in a horizontal position, said arm normally will not yield to the pressure exerted thereupon by the spring 43 and the torsion of this spring, therefore, is ex-

10 tended in producing a downwardly acting impulse upon the arm 14, owing to which impulse the lens correlated with said arm will be held in a constant firm contact with the correlated grinding tool 26.

15 The grinding tools 26 shown in the drawings are so formed as to produce concave or minus cylinder lenses, but it is, of course, to be understood that the machine may be employed to form convex cylinder lenses by 20 substituting a grinding tool of a suitable form. The arms 6 will preferably be subjected to a reciprocating motion three times as rapid as the motion which is communicated to the arm 22, it having been found 25 that these relative motions of the parts specified serve to produce the most satisfactory results. In order to prevent expansion of the spring 43 when the parts correlated therewith occupy the position shown in dash 30 lines in Fig. 11, a flexible strap 44 is extended between the two arms 14 and 37.

The dash line construction illustrated in Fig. 11 shows the position occupied by the mechanism for exerting downward pressure 35 upon the lens, when said mechanism is not in use.

The invention is presented as including all such modifications and changes as properly come within the scope of the following 40 claims.

What I claim is:

1. In a lens grinding and polishing machine, the combination of, a base, a work

support, a tool support, said supports reciprocating over the base at right angles to each other, a tool mounted on the tool support, a work carrier hinged on the work support over the tool, a member supported in hinged relation to the base, an arm 45 mounted on the hinged support, and a resilient connection between the arm and the hinged work carrier.

2. In a lens grinding and polishing machine, the combination of, a base, a work support, a tool support, said supports reciprocating over the base at right angles to each other, a tool mounted in the tool support, a work carrier hinged on the work support over the tool, a member supported in hinged relation to the base, an arm 50 55 mounted on the hinged support, a resilient connection between the arm and the work carrier, and a spring held latch connected to the arm and arranged to lock the same in adjusted positions.

3. The combination in a lens grinding and polishing machine, of a base, a main crank shaft mounted on the base, a counter crank shaft mounted on the base at right angles to the main shaft, a work member connected to 60 the main shaft, a work carrier hinged on the end of the work member, an arm hinged over the base, a resilient connection between the arm and the hinged work carrier, a tool carrier connected to the counter shaft, 65 a tool mounted on the tool carrier under the work carrier, and a gearing connection between the two shafts.

In testimony whereof I have signed my name to this specification in the presence 70 of two subscribing witnesses.

ALMER A. ROUSSEAU.
